[57] CLAIM

The ornamental design for a tub shell or the like, as shown and described.

DESCRIPTION

FIG. 1 is a perspective view taken from the top, front and right side of a tub shell or the like showing my new design;

FIG. 2 is an alternate perspective view taken from the top, rear and left side thereof;

FIG. 3 is a top plan view thereof;

FIG. 4 is a cross-sectional view taken on line 4—4 of FIG. 3;

FIG. 5 is a cross-sectional view taken on line 5—5 of FIG. 3; and

FIG. 6 is a top plan view of a second embodiment of my new design, the second embodiment differing from the first only in length.

FIG. 1

FIG. 2

FIG. 3

FIG. 4

FIG. 5

FIG. 6
